UNITED STATES PATENT OFFICE.

MORITZ GROSS AND BERNHARD B. ZIPPERT, OF NEW YORK, N. Y.

DESIGN FOR A LADY'S FUR COLLAR.

Specification forming part of Design No. 6,827, dated August 26, 1873; application filed June 28, 1873.

To all whom it may concern:

Be it known that we, MORITZ GROSS and BERNHARD B. ZIPPERT, both residents of the city, county, and State of New York, have invented a Design for Ladies' Fur Collars, of which the following is a specification:

The nature of the invention is fully represented in the accompanying drawings, to which reference is made, and in which—

A represents the portion encircling the neck, and is made of fur or other suitable material, and having through or on its center, as shown, a stripe of fur differing in color, or a fancy cord—said stripe marked B. At one end of said collar is the portion marked C, having a rosette, marked D, of fur, with button or other device in center, and below this widening out, as shown, with a center, E, of fur or silk, bordered with an edging of fur, as shown, and marked G, also having a fancy cord, as shown at B'; but it may be made without the cord, if desired, and entirely of fur; and at the lower end of said collar, pendent therefrom, we attach fringe of any suitable material, and about as shown, and marked H.

The colors may vary to suit taste.

What we claim as new is—

The design for a lady's fur collar, substantially as shown and described.

MORITZ GROSS.

BERNHARD B. ZIPPERT.
